UNITED STATES PATENT OFFICE.

OTTO HAŠSELMANN, OF WIESBADEN, GERMANY.

CONTAINER FOR STORING MEDICAL INJECTION NEEDLES.

Application filed November 5, 1925. Serial No. 67,143.

To all whom it may concern:

Be it known that I, OTTO HAŠSELMANN, a German citizen, and residing at Wiesbaden, Germany, have invented certain new and useful Improvements in a Container for Storing Medical Injection Needles (for which I have filed an application in Germany on 5th November, 1924, Patent No. 418,149), of which the following is a specification.

- 10 This invention relates to an improved container for storing medical injection needles, of the known kind in which a plurality of needles are inserted with oppositely directed points.
- 15 According to the invention, the container comprises an integral framing having two end rings and a middle guiding ring, in which the needles are inserted and together with which they can be sterilized, while on one 20 of said end rings two caps are screwed from opposite sides, whereby the container is closed and divided into a septic and into an aseptic compartment for a separate reception therein of used and of fresh sterilized needles respectively.

The accompanying drawing illustrates the improved container: Fig. 1 is a longitudinal section of the same on the line 1—1 of Fig. 2, which is a section on the line 2—2 of Fig. 30 1 seen in the direction of arrow.

The improved container comprises an integral framing having two end rings *a*, *c* and a middle guiding ring *b*. The end rings *a*, *c* have each a plurality of, for instance 35 four as shown, longitudinal borings *a'*, *c'* respectively therein, of which those in one ring are arranged in staggered position with reference to those in the other ring, while the middle guiding ring *b* is provided with 40 double the number of corresponding longitudinal borings *b'* coinciding with those in the end rings.

The injection needles *x*, *x'* to be stored in the container can be inserted with oppositely directed points from both ends of the framing, the borings in said rings being provided with countersunk introduction ends. The needles, being inserted, can then be sterilized together with the framing.

One of said end rings, for instance *a*, is 45 fitted with a flange *a¹* and with screw-threads *a²* on both sides of the latter, while two caps *d*, *e* can be screwed on said screw-threads from opposite sides, whereby the container is closed and divided into two 50 separate compartments, namely an aseptic one for the reception of fresh sterilized needles *x* and a septic one for the reception of used needles *x'*.

The used and fresh sterilized needles can 55 thus not touch each other, and the small water drops left after completed sterilization in the countersunk introduction ends of the ring borings prevent by their co- and adhesion a transmission of impurities from 60 the used to the still fresh sterilized needles in the container.

What I claim is:

A container for storing medical injection needles, comprising, in combination, an integral framing having two end rings and a middle guiding ring, and two closing caps 70 screwed on one of said end rings from opposite sides thereby dividing the container into two separate compartments, said rings having longitudinal borings with countersunk introduction ends therein of which those in one end ring are arranged in staggered position with reference to those in the other end ring, substantially as and for the purpose set forth.

In testimony whereof I have hereunto set my hand.

OTTO HAŠSELMANN:
